UNITED STATES PATENT OFFICE.

CHARLES F. GRAY, OF SIERRA MADRE, CALIFORNIA, ASSIGNOR TO THE SINGER MANUFACTURING COMPANY, A CORPORATION OF NEW JERSEY.

SEWING-MACHINE CLOTH-PRESSER.

1,202,283.

Specification of Letters Patent. Patented Oct. 24, 1916.

Application filed February 12, 1914. Serial No. 818,197.

To all whom it may concern:

Be it known that I, CHARLES F. GRAY, a citizen of the United States, residing at Sierra Madre, in the county of Los Angeles and State of California, have invented certain new and useful Improvements in Sewing-Machine Cloth-Pressers, of which the following is a specification, reference being had therein to the accompanying drawings.

10 This invention relates to improvements in sewing machine cloth-pressers for multiple needle sewing machines, and has for its object to provide a device especially adapted to the requirements of multiple seam products in which one of the seams is arranged in line with and in close proximity to a fold in the fabric being acted on, the fold acting to determine the relative arrangement of the complementary seams.

20 Referring to the drawings, Figures 1, 2, 3 and 4 are views in front elevation, side elevation, rear side elevation and in a plan, respectively of the present invention, and Fig. 5, one variety of product herein shown for a better understanding of the invention.

Referring to the figures, 1 represents the ordinary cloth-press-carrying-bar mounted in suitable bearings formed in the head 2 of one form of commonly employed bracket-arm (not shown), the usual spring 3 and collar 4 being employed to yieldingly hold the presser-foot down upon the fabric, the presser lifting lever 5 acting, at the will of the operator, on the extended portion 6 of the collar to elevate said bar.

7 represents the presser-bar bracket secured by screw 8 to the bar 1, said bracket being cut out at 9 to receive the latter bar and at its opposite ends provided with bearings as 10 into which are loosely mounted the cloth-presser-carrying rods 11 and 12, each of the latter being provided with guide-collars, as 13, secured on said rod by screws, as 14, each of said collars being provided with guide-members, as 15, which track suitable guide-slots, as 16, formed in the bracket 7; springs, as 17, acting on the collar 13 to yieldingly hold the rocking presser-feet 18 and 19 in their depressed positions.

20 and 21 denote presser-feet brackets carried by the rods 11 and 12 respectively, and into said brackets are pivotally connected by pivot pins, as 22, the respective presser-feet 18 and 19, each of the latter being provided

with needle openings, as 23, and needle-thread slots, as 24.

25 represents the guiding presser-foot bracket secured by screw 26 and pins, as 27, to the rear side of the bracket 7, and to the free end of the bracket 25 is pivotally connected by pin 28 the guiding presser-foot 29 provided with the needle opening 30, V-shaped opening 30' and guiding walls 31 and 32, the receiving end of each of the cloth-pressers being turned upward to better accommodate the feeding of the fabric to the action of the needle.

The fabrics represented by 33 and 34, Fig. 5, comprise portions of a corset as commonly assembled; 36 denoting the stay-pocket tape and 37 the rust-proof fabric with which the inner sides of the stay-pockets, as 38, are lined, the two portions 33 and 34 being provided with edge-folds which are superposed to receive the seam *a*, the latter also acting to secure to said portions the fabrics 36 and 37, such operations being known in corset construction parlance as "the joining operation", the seam, as *b*, acting to secure the fabrics 36 and 37 to the joined portions 33 and 34 which form the pockets 38, thus the seams, as *b*, are formed in four plies of fabric while the seam *a* comprises six plies, and further, in the manufacture of corsets it frequently occurs that the body portions 33 and 34 are folded or joined by seams arranged transverse to and crossing the present seams which further complicates the problem of securely holding the fabrics down upon the usual cloth-plate and to overcome this difficulty is the purpose of the present invention.

To unite the fabrics as represented by Fig. 5, the free edge 40 of the fold 41 tracks the vertical guide-wall 32 of the presser 29, thus insuring that the several seams will be properly gaged, but should the joining operation include portions, having the free edge of the fold of the upper ply at the left of the seam *a*, such free edge would, of necessity, be directed by the guide-wall 31.

To better adapt the present device to an organized sewing machine for effecting a central chain-stitch and two outer lock-stitch seams, as in my pending application, Serial No. 817,737, filed Feb. 19, 1914, for improvements in sewing machines, the cloth-pressers 18 and 19 are provided with slots,

as 24, to make convenient the passing of the needle-thread back under the respective pressers without being obliged to thread through the needle holes 23, but as the central presser 29 coats with the chain-stitch or seam *a*, it is preferable to omit slotting the cloth-presser as it is desirable that the presser present a solid surface directly above the fold or otherwise the free edge 40 10 would ride the opening above the under surface of the presser and tend to distort the fold, vary the gage and interfere with the formation of the stitch. As is evident from the functions claimed for the respective 15 pressers, the spring 3 must be of sufficient strength to resist the power exerted by the springs 17.

Having thus set forth the nature of the invention, what I claim herein is:—

- 20 1. In a cloth-presser mechanism for sewing machines, the combination with a main spring-depressed presser-bar carrying a rocking cloth-presser having a needle opening comprising a continuous wall, of independently mounted spring-depressed rocking cloth-pressers having independent 25 depressing means and located one at one side and the other at the opposite side of the cloth-presser carried by said main presser-bar.
- 30 2. In a cloth-presser mechanism for sewing machines, the combination with a main spring-depressed presser-bar carrying a rocking cloth-presser having a needle-opening comprising a continuous wall and a V-shaped opening at its receiving end terminating in guide-walls, of spring-depressed rocking cloth-pressers having independent 35 depressing means and located one at one side and the other at the opposite side of the cloth-presser carried by said main presser-bar.

from their receiving ends into the needle-opening.

2. In a cloth-presser mechanism for sewing machines, the combination with a main spring-depressed presser-bar carrying a rocking cloth-presser provided with oppositely arranged guide-walls, of independently mounted spring-depressed cloth-pressers having independent depressing means and arranged one at one side and the other at the opposite side and normally below the cloth-presser carried by said main presser-bar. 40

3. In a cloth-presser mechanism for sewing machines, the combination with a main spring-depressed presser-bar carrying a rocking cloth-presser having a needle-opening comprising a continuous wall and a V-shaped opening at its receiving end terminating in guide-walls, of spring-depressed rocking cloth-pressers having independent 45 depressing means and located one at one side and the other at the opposite side of the cloth-presser carried by said main presser-bar. 50

In testimony whereof, I have signed my name to this specification, in the presence of two subscribing witnesses.

CHARLES F. GRAY.
